H. C. EGERTON.

RECEIVER CASE,

APPLICATION FILED FEB. 7, 1916.

1,232,515.

Patented July 10, 1917.

Invenior:
Henry C. Egerton
by of C. Danes, ATT'y.

UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

RECEIVER-CASE.

1,232,515.

Specification of Letters Patent. Patented July 10, 1917.

Application filed February 7, 1916. Serial No. 76,739.

To all whom it may concern:

Be it known that I, HENRY C. EGERTON, a citizen of the United States, residing at Passaic, in the county of Passaic and State 5 of New Jersey, have invented certain new and useful Improvements in Receiver-Cases, of which the following is a full, clear, concise, and exact description.

This invention relates to receiver cases and 10 more particularly to those provided with a plurality of independent and separable chambers.

The object of this invention is the provision of a receiver case, having a magnet chamber self-contained and independent of 15 another self-contained structure by means of which said magnet chamber may be removably mounted.

In accordance with this invention, there is 20 provided a magnet chamber consisting of two hollow metal sections having a gasket interposed therebetween, thus making a moisture-proof receptacle for the receiver magnet. Coöoperating with the magnet 25 chamber is a conductlet, comprising a hollow structure having a plurality of openings. One of said openings is closed by said magnet chamber being placed thereover, and the joint formed thereby is made moisture-proof 30 through the agency of a rubber gasket. The remainder of said openings are threaded to receive threads formed upon the end of a conduit. Suitable attaching means is provided with the conductlet to permit its mounting 35 in a convenient location.

In the accompanying drawing, Figure 1 is a back elevation partly in section, of a receiver case embodying the features of this invention, and Fig. 2 is a side elevation of 40 the device shown in Fig. 1.

The receiver case shown in the drawing comprises a magnet chamber 1 formed of two hollow metallic sections 2, 3 having their edges provided with a flange 4, 5 respectively, suitable for registering with each other. The flange 4 has a plurality of apertures, while the flange 5 has a corresponding number of threaded recesses suitable to engage screws, which function to secure the 45 sections 2, 3 together. Interposed between the flanges 4, 5 is a rubber gasket 6 which serves to make the magnet chamber moisture-proof. An annular boss is formed upon the front of section 2, which is fitted with 50 reducing collars adapted to accommodate an

amplifying horn. Terminals 7 and 8 are provided in the base of section 3 for connecting the electromagnet of the receiver in an energizing circuit. The apparatus comprising the microphone element forms 60 no part of this invention and may be of any standard construction suitable for mounting within the magnet chamber 1.

The magnet chamber 1 is attached to a conductlet 9, consisting of a hollow receptacle 65 provided with a flange 10 adapted to fit the base portion of section 3. A rubber gasket 11 is inserted between the engaging surfaces of the flange 10 and section 3, thereby making their union moisture-proof. The portion of the conductlet 9 adjacent a flange 10 is substantially cylindrical in shape, and is provided with openings 12, 12 coinciding with its longitudinal axis. These openings are threaded for the accommodation of the 70 threaded end of a conduit 13. If it is not desirable to attach a conduit to each of the openings 12, 12, a threaded plug 14 may be inserted into the vacant one. It will be apparent that when the various elements carried by the conductlet 9 are assembled, a moisture-proof chamber is provided for housing the terminals and conductors by means of which the receiver chamber is connected in an energizing circuit. Depending from the 75 body portion of the conductlet 9 is a plurality of legs 15 provided with openings through which screws may be inserted for fastening the receiver case in any desired location.

From the above it will be seen that a receiver case embodying the features of this invention is provided with two separate self-contained moisture-proof chambers capable of being detached and used independent of each other or in connection with similar associated parts.

What is claimed is:

1. In a receiver case, the combination with a magnet chamber, of a conductlet consisting of a hollow structure having a plurality of 100 openings, one of said openings being completely closed by said magnet chamber positioned thereover, and another of said openings adapted to receive one end of a conduit.
2. In a receiver case, the combination with a magnet chamber, of a conductlet consisting of a hollow structure having a plurality of 105 openings, one of said openings being completely closed by said chamber positioned thereover, means for making the joint be- 110

tween said magnet chamber and said opening moisture-proof, and another of said openings adapted to receive one end of a conduit.

- 5 3. In a receiver case, the combination with a moisture-proof magnet chamber, an electromagnet located within said chamber, a leading-out terminal for connecting said electromagnet in an energizing circuit, said 10 terminal being secured to the base of said magnet chamber, of a condulet consisting of a hollow structure having a plurality of openings, one of said openings being closed by said magnet chamber positioned thereby 15 over, and another of said openings adapted to receive one end of a conduit.

4. In a case for telephonic apparatus, the combination with an apparatus chamber of a condulet consisting of a hollow structure having a plurality of openings, one of said 20 openings being completely closed by a wall of said apparatus chamber positioned there-over, a leading-out terminal secured to said wall and positioned within said hollow structure, and another of said openings in said 25 hollow structure adapted to receive one end of a conduit.

In witness whereof, I hereunto subscribe my name this 5th day of February A. D., 1916.

HENRY C. EGERTON.
